UNITED STATES PATENT OFFICE.

WILLIAM S. BATES, OF CHICAGO, ILLINOIS.

DESIGN FOR A PUZZLE.

SPECIFICATION forming part of Design No. 25,350, dated April 7, 1896.

Application filed November 29, 1895. Serial No. 570,560. Term of patent 7 years.

To all whom it may concern:

Be it known that I, WILLIAM S. BATES, of Chicago, Illinois, have invented and produced a new and original Design for a Puzzle, whereof the following is a specification.

My design comprises a circular body of disk form having upon the upper surface a flat volute band starting from the center and terminating at a point near the periphery, the outer end of said volute band joining the next inner coil thereof. Placed upon the said disk is a link, one member of which passes beneath the volute band upon the surface of the disk.

In the drawings, Figure 1 is a top view, and Fig. 2 is a section on line 2 2 of Fig. 1.

1 is the disk.

2 is the volute band starting at 3 from the center of the disk and terminating at 4, near the periphery, where its end joins the next inner coil.

5 is the link placed on the disk, and having one member passing beneath the volute band, as shown.

I claim—

The design for a puzzle herein shown and described.

WILLIAM S. BATES.
